UNITED STATES PATENT OFFICE.

WILLIAM O. HORN, OF NEW YORK, N. Y.

DESIGN FOR A COLLAR.

SPECIFICATION forming part of Design No. 34,233, dated March 19, 1901.

Application filed February 7, 1901. Serial No. 46,455. Term of patent 3½ years.

To all whom it may concern:

Be it known that I, WILLIAM O. HORN, a citizen of the United States, residing in the city, county, and State of New York, have invented and produced a new and original Design for Collars, of which the following is a specification, reference being had to the accompanying drawings, forming part thereof.

The leading feature of my design for a collar, known as a "high collar for ladies," is a folded collar having its neckband of comparatively the same height throughout its length, closed in front and open at the rear and the outward member divided in front and open at the rear and having the lower edges of its sections extending in an unbroken curve from the closed front of the neckband upwardly to the rear and terminating in points.

Figure 1 represents a perspective view of a collar embodying my design. Fig. 2 represents a vertical section thereof on line *x* *x*. Fig. 3 represents a plan view of the collar in extended condition on a reduced scale.

In the drawings, A designates a folded collar composed of the neck or inner member B and the outer member C, said outer member being divided in front, as at D, forming the sections E E, the lower edges F of which are deflected upwardly, thus decreasing the height of said sections from the front to the rear, 25 said edges extending in an unbroken curve upwardly from front to rear and terminating in points at said rear. The neck or inner member B is comparatively of the same height throughout its length. 30

Having thus described my invention, what I claim as new, and desire to secure by Letters Patent, is—

The design for a collar substantially as shown and described.

WILLIAM O. HORN.
